DOUBLE PIVOT LAST COMPANY, OF AUBURN, MAINE, A CORPORATION OF MAINE.

SELF-LOCKING LAST.

1,426,428.

Specification of Letters Patent. Patented Aug. 22, 1922.

Application filed January 29, 1919. Serial No. 273,745.

To all whom it may concern:

Be it known that I, RALPH C. WEBSTER, a citizen of the United States, residing at Haverhill, in the county of Essex and State of Massachusetts, have invented new and useful Improvements in Self-Locking Lasts, of which the following is a specification.

This invention relates to lasts used in shoemaking, and has particular reference to lasts of the type which are divided in a manner such as to permit relative movement between the heel part and fore part whereby to shorten the last and enable it to be easily and harmlessly removed from a lasted shoe. The particular object of the invention is to provide a last of this type with self-locking means for holding it extended with perfect rigidity, which means may at need be released to permit shortening or breaking of the last, without the use of an instrument of any kind, and without need of providing an external movable handle or trigger. In further explaining this object I will say that although numerous lasts have been made which are capable of being extended for use and collapsed or shortened for withdrawal, yet in all such lasts so far as I am aware, the parts when extended are either not rigidly held so that they can not be collapsed by a powerful enough external force, or if they are rigidly so held, the locking or bracing means requires to be displaced with the aid of a tool before the last can be collapsed, and in forms where a separate tool for this purpose is not required, a substantially equivalent contrivance in the nature of a trigger or lever projecting externally from within the last is provided. The advantages of a last which is rigidly locked when in the extended position are obvious; and so is the objection to the need for using a separate tool in order to lock and unlock the extended last. These factors have led to the development of collapsible lasts having rigid locking means with integral or otherwise permanently associated trigger contrivances which project from the comb of the last and are adapted to be moved by manipulation in order to set and release the lock. But such contrivances also have their disadvantages. Although they are not susceptible of being mislaid, yet they may very easily be bent or broken and so made inoperative, or they may be accidentally released at wrong times, and their very presence necessitates providing an opening which may

be entered by odds and ends of rubbish with the effect of clogging and interfering with the operation of the latch or controlling trigger and of the lock itself. 60

Principal objects of my invention are to furnish a simple, novel lock which is not only rigid and not liable to be released by any externally applied force however great, less than sufficient to break the last itself, 65 but can be released or set without the use of separate tools which is also entirely enclosed within the last body: and which may be operated by gravity alone, making unnecessary the provision of any passages or 70 recesses of any sort opening at an outer surface of the last. The manner in which these purposes are accomplished appears from the following description of a preferred form of last selected for illustrative 75 purposes, in which the invention is embodied. My last comprises a forepart, a heel part, arranged for relative movement to collapse or extend the last, and a locking device for holding the last in extended position operated by gravity. In the last shown, 80 a locking member is entirely enclosed and protected within the body of the last, whereby accidental displacement and clogging by dirt are prevented, and is not attached to 85 any other part, falling freely, by gravity, into operative or inoperative position. In the accompanying drawings,

Figure 1 is a fragmentary side elevation of a last partly broken away to illustrate 90 the form of the lock containing my invention hereinbefore referred to. Figure 2 is a cross section on line 2-2 of Figure 1. Figure 3 is a cross section on line 3-3 of Figure 1. Figure 5 is a view similar to Figure 1 but 95 showing the parts of the last in their displaced or collapsed condition. Figure 4 is a perspective view of the connector between the fore and heel parts of the last.

Like reference characters represent the 100 same parts wherever they occur in all the figures.

Referring to the drawings *a* represents the fore part and *b* represents the heel part of a divided last, the plane of the division between these parts coinciding with the line 105 3-3. This dividing plane is inclined to the longitudinal axis of the last in order that when one part is moved relatively to the other along this plane, the distance in a 110 straight line between the extreme opposite points will be shortened or lengthened as the

case may be. So far as the present invention is concerned it is not material in which direction this plane is inclined. The parts *a* and *b* are coupled together in a sliding manner by means of a connector *c* which is set into the forward end of the heel part and is secured therein by cross pins *d* in a well understood manner, and has a part *c'* which fits and slides in a guideway in the 10 rearward end of the fore part. This sliding part is here shown as being cylindrical and of greater diameter than the thickness of that part of the connector which is set into the heel part, but it may be made otherwise, 15 provided only it and the complementary guideway in the fore part extend parallel to the plane of division and are so made as to be interlocked, preventing one part of the last being separated from the other part. 20 In this drawing the guideway for said slide is shown as being a tube *e* which is set into a cylindrical hole in the fore part and is provided with a slot *f* in its rear side through which the web of the connector 25 passes and in which such web slides freely. Of course the connector may be reversed without departure from the essence of the invention, the web of the connector being then set into the fore part and the guideway being set into the heel part.

The brace or lock for securing the parts of the last in their extended position, that shown in Figure 1, is a form of ball clutch consisting of a ball *g* which co-acts with the 35 connector *c* and with the guideway *e*. The latter has an opening *h* in its side toward the heel part and in communication with the slot *f*. This opening may be considered as an enlargement of the slot, and it is sufficiently long and wide to permit the ball to roll through it. The wall of the tube below this opening or enlargement forms an 40 abutment, or a pair of symmetrically arranged abutments *k*—*k* (see Figure 3), and these abutments are located in the construction 45 illustrated at opposite sides of the lower part of slot *f*. And in the web of the connector there is a pocket *m* the bottom of which also forms an abutment, and is slightly above the lower end of the slide *c'* and the rear side of which is in rear of the abutments *k*—*k* by a distance slightly greater than the radius of the ball. The abutments *k*—*k*, which define the lower limit of the opening 50 or enlargement *h* are arranged in a position to permit the ball to pass over them into the pocket *m* when the fore part is very slightly beyond its lowered or fully extended position with respect to the heel part of the 55 last, and the ball may be caused to pass into this pocket by gravity upon turning the last to bring the heel part downward. Then the ball occupies substantially the position shown in Figures 1, 2, and 3, where its center is in rear of the abutments *k*—*k* and it

is confined between such abutments and the abutment formed by the bottom and rear of the pocket. It is held in this position by the pressure of a spring *n* which occupies the upper part of the guideway *e* and presses 70 against the slide *c'*, reacting upon an abutment in the form of a pin *o* set into the fore part and crossing the passageway or hole in which the guide is located. Obviously this spring presses the connector against 75 the ball and the ball against the abutments *k*—*k*, tending always to press the abutments at *k* and *m* toward one another, whereby the last is locked in its extended position without any possibility of becoming unlocked, 80 because the depth of the pocket *m* above the bottom of the slide *c'* altogether prevents slipping of the ball past the abutment shoulders into the guideway.

In order to release the lock it is necessary only to move the fore part *b* slightly toward the bottom of the last, a distance just enough to relieve the pressure against the ball and enlarge the space between the bottom of slide *c'* and the abutment shoulders *k*, *k* enough to permit the ball to pass, and then tilt the last so that the toe points downward. The ball will then roll into the guideway and leave the parts unlocked, as shown in Figure 5, whereby one of the parts 95 is able to slide past the other in the manner required for shortening the last. The above described movement of the fore part necessary to release the ball clutch is very slight, and the pocket *m* may, by proper design, 100 be made of such depth that, although the ball is securely locked in it when in the position indicated in Figure 1, yet the ball may be released by movement of the fore part so slight as to be almost imperceptible and 105 well within the limit of movement permitted by the stretching capacity of the shoe upper. In these drawings the depth of the pocket *m* above the bottom of slide *c'* is somewhat exaggerated in order to illustrate clearly the 110 principles of the invention.

It will be apparent from this explanation that my invention provides a form of lock which is absolutely positive, and which is capable of being made of strength great 115 enough to prevent collapsing or shortening of the last by any force externally applied, however great, within the limit of strength of the last itself. That is, the lock may be made so strong that some part of the last 120 itself will break under applied force before the lock will give way. At the same time the lock may be set and released by simple manipulation, that is, holding the parts so as to clear the opening *h* for passage of the 125 ball, and then tilting the last heel downward or toe downward as the case may be; wherefore, no tools or implements are required for this purpose. And finally, the lock is entirely enclosed within the material 130

of the last and between the parts thereof, having not even an exposed trigger or handle, and therefore not liable to become obstructed by dust and rubbish, and not liable 5 to be injured by the careless handling and knocking about to which lasts are subject in a shoe factory. Although the necessary method of boring the hole in which the guideway *e* is set leaves one end of the hole 10 open at an outer surface of the last, yet such open end may be closed by a plug *p* without interference with any of the movable parts; whereby entrance of rubbish is altogether excluded.

15 Of course it is to be understood that the foregoing explanation, and particularly the terms indicating direction and relative height and positions of the various parts are used with reference to the position of 20 the last shown in the drawings; this position being that corresponding to the usual position of the finished shoe, but the reverse of the position which the last occupies during 25 most of the operations of shoemaking in which it is employed. I would point out further that nothing in the foregoing description is to be construed as limiting my 30 claim to protection to the precise form and arrangement of the elements here shown, or 35 to exclude from the scope of such protection all rearrangements, reversals in position and directions of movement, and modifications in form of the various parts, which have essentially the same or equivalent functions 40 and mode of operation of the parts here described. The last here exhibited comprises a sliding connection between the fore part and the heel part, with a ball clutch adapted 45 to be gripped between shoulders or abutments of such sliding connection, such abutments tending to approach one another as the last collapses, and adapted to be released from between such abutments; and the positioning and release of the ball are adapted 50 to be effected by gravity. Any element capable of performing any or all of the functions of the ball *g*, whether actually made as a sphere or a cylinder, or of other shape, is within the protection of the term "ball" 55 as hereinafter used in the appended claims.

The functions thus referred to are of course those of advancing into and withdrawing from a recess in one of the parts, by gravity, being always wholly or partly 55 retained within the last; of being interposed between abutments on the heel part and fore part respectively when thus advanced, thereby locking parts in the lengthened position; and of being confined and secured in 60 its locking position by the pressure applied against it from opposite sides by said abutments under the force of the spring. It is likewise to be noted that the spring *n* has an important function causing the ball to 65 be gripped between the abutments when in

the locking position with the last extended, whereby the ball is prevented from falling back from the locking position and the last is thus prevented from becoming accidentally unlocked.

70 Another function of the spring in the preferred arrangement here shown is that it tends to move the complementary parts in a manner which shortens the last, and helps the operator to remove the last from a lasted 75 shoe.

Although the recess or pocket *m* is shown in the web *c* of the connector, yet it is properly to be considered as formed or provided in the heel part, since this web is essentially 80 part of the heel part; and the pocket may equally well be formed otherwise than in the specific manner shown. In case of reversal of the construction the pocket would be made in the fore part. My broader claims 85 are thus to be construed as including all constructions in which abutments for a locking piece are formed or provided in the parts of the last in any manner; but I also claim the locking piece, which is preferably 90 made of steel, within a metal-lined chamber, and between metal abutments when the last is locked in extended position; for both the connector and the guideway are preferably 95 made of metal. Such metallic parts 100 evidently have much greater rigidity and durability than constructions in which the locking piece abuts against non-reinforced shoulders or pockets in the parts of a last made of wood.

What I claim and desire to secure by Letters Patent is:

1. A last comprising fore and heel parts 105 permanently connected together with provision for relative movement in a manner to permit shortening and lengthening of the last, said parts having opposed abutments adapted to receive between them a locking piece when the parts are in the extended position, a locking piece permanently 110 contained wholly or partly in one of said parts and adapted to be entered between or withdrawn from between said abutments by gravity, and a spring applying force in relatively opposite directions upon the respective parts, whereby to press the abutments against the locking piece when the latter is placed between them.

2. A last comprising a fore part and a heel part, a sliding connection between such parts having relatively movable abutments or shoulders, and a lock adapted to be placed between said abutments or shoulders when said parts are extended, thereby locking them 120 in extended position, and to be displaced therefrom to permit collapse or shortening of the last, said lock being movable into its locking and unlocking positions by gravity and being entirely enclosed within the body 125 of the last.

3. A last comprising a fore part and a heel part, a slide connected to one of said parts, a guide connected to the other of said parts with which said slide is movably associated, and a locking piece, the parts of the last having complementary abutments between which the locking piece may be placed when said parts are extended, whereby to lock them in extended position, and from 10 which the locking piece may be displaced, and a spring acting upon said parts and applying force through said abutments to grip the locking piece.

4. A last comprising a fore part and a heel part divided by a plane inclined to the longitudinal axis of the last, a guideway set into the abutting end of one of said parts, a slide fitting movably in said guideway and connected to the contiguous abutting 20 end of the other of said parts, and a ball occupying the guideway adjacent to one end of said slide, said guideway having an opening and an abutment bounding said opening in the side toward the other of the parts, through which opening and between said abutment and the end of the slide the ball may pass when the parts of the last are extended, and the other of said last parts having a pocket to receive the ball 30 and confine it in locked contact with said abutment.

5. A last comprising a fore part and a heel part divided by a plane inclined to the longitudinal axis of the last, a guideway set 35 into the abutting end of one of said parts, a slide fitting movably in said guideway and connected to the contiguous abutting end of the other of said parts, a ball occupying the guideway adjacent to one end of said 40 slide, said guideway having an opening and an abutment bounding said opening in the side toward the other of the parts, through which opening and between said abutment and the end of the slide the ball may pass 45 when the parts of the last are extended, and the other of said last parts having a pocket to receive the ball and confine it in locked contact with said abutment, and a spring 50 acting upon the parts of the last and applying force upon the slide toward said ball.

6. A last comprising a heel part and a separate fore part abutting against one another on a plane inclined to the length of the 55 last, a metal connector set into one of said parts, a metal guideway with which said connector is interlocked and in which it is adapted to slide along said plane, and a locking ball adapted to pass into and out 60 of said guideway when the parts are fully extended; the connector having a recess to receive the ball and the guideway having an abutment between which and the bottom of said recess the ball is gripped when 65 in locking position.

7. A last comprising separate fore and heel parts connected together in a manner to permit relative movements in opposite directions to cause shortening and lengthening, respectively, of the last, and a metal 70 locking piece contained inaccessibly within the last, said parts having metal abutments arranged to receive said piece between them when the last is extended or lengthened in a manner and position to oppose positive 75 resistance to the shortening relative movement of said parts.

8. A last comprising separate fore and heel parts connected together in a manner permitting relative movements for respectively 80 shortening and lengthening the last, a locking piece, opposed metal abutments in the fore part and heel part adapted to be so placed when the last is lengthened that the locking piece may enter between them, the 85 said parts having spaces adjacent to the abutments in which the opposite extremities of the locking piece are then received, and into one of which the entire locking piece may be withdrawn by the action of gravity 90 preparatory to shortening the last.

9. A last comprising fore and heel parts connected together with provision for relative movement in a manner to permit collapsing and extending the last, and a locking member to hold the last in extended position, said member being constructed and arranged to roll into and out of operative 95 position under the action of gravity.

10. A last comprising fore and heel parts 100 connected together with provision for relative movement in a manner to permit collapsing and extending the last, and a locking member inaccessibly mounted within the last constructed and arranged to hold the 105 last rigidly in extended position.

11. A last comprising a forepart and a heel part, a bonding mechanism between such parts having relatively movable abutments or shoulders, and a lock adapted to be 110 placed unyieldingly between said abutments or shoulders when said parts are extended, thereby locking them in extended position, and to be displaced therefrom to permit collapse or shortening of the last.

12. A last comprising a forepart and a heel part, a connection between such parts having relatively movable abutments or shoulders, and a lock adapted to be placed between said abutments or shoulders when 120 said parts are extended, thereby locking them in extended position, and to be displaced therefrom to permit collapse or shortening of the last, said lock being movable into its locking and unlocking positions by 125 gravity.

13. A last comprising a forepart and a heel part, a connection between such parts having relatively movable abutments or shoulders, and a lock adapted to be placed 130

between said abutments or shoulders when said parts are extended, thereby positively locking them in extended position, and to be displaced therefrom to permit collapse or 5 shortening of the last, said lock being sealed within the body of the last.

14. A last comprising a forepart and a heel part, a connection between such parts having relatively movable abutments or 10 shoulders, and a lock adapted to be placed between said abutments or shoulders when said parts are extended, thereby locking them in extended position, and to be displaced therefrom to permit collapse or short- 15 ening of the last, said lock being movable into its locking and unlocking positions by gravity and being entirely enclosed within the body of the last.

15. A last comprising fore and heel parts 20 connected together with provision for relative movement in a manner to permit collapsing and extending the last, said parts having a runway with parts constituting opposed abutments adapted to receive between them a locking piece when the last is in extended position, and a locking piece freely movable by gravity in said runway between or from between said abutments.

16. A last comprising fore and heel parts 30 connected together with provision for relative movement in a manner to permit collapsing and extending the last, said parts having opposed abutments adapted to receive between them a locking piece when the 35 last is in extended position, and a locking piece inaccessibly contained within the body of the last and constructed and arranged to be entered between or withdrawn from between said abutments solely by the action 40 of gravity.

17. A last comprising fore and heel parts connected together with provision for relative movement in a manner to permit shortening and lengthening of the last, said parts 45 having opposed abutments adapted to receive between them a locking piece when the last is in extended position, said parts being constructed and arranged to fit together and to provide no apertures leading to the interior of the last, and a locking member entirely concealed within the last and con-

structed and arranged to co-operate with the abutments to hold the last positively in extended position.

18. A last comprising fore and heel parts 55 connected together with provision for relative movement in a manner to permit shortening and lengthening of the last, said parts having opposed abutments arranged to approach each other as the last collapses, and a concealed locking member moving freely within the last constructed and arranged to co-operate with said abutments to hold the last in extended position.

19. A last comprising fore and heel parts 65 connected together with provision for relative movement in a manner to permit shortening and lengthening of the lasts, said parts providing an enclosure and having opposed abutments arranged to approach each 70 other as the last collapses, and a locking member unattached to either last part and confined in said enclosure constructed and arranged to move under the action of gravity between and from between the abutments 75 to lock and release the last parts respectively.

20. A last comprising fore and heel parts connected together with provision for relative movement in a manner to permit shortening and lengthening of the last, and a concealed locking member moving freely within the last constructed and arranged 80 to hold the last in extended position.

21. A last comprising fore and heel parts 85 connected together with provision for relative movement in a manner to permit collapsing the last, and a locking member unattached to the last parts and movable by gravity freely within the last into and out 90 of operative position to hold the last in extended position or to release it for collapsing movement respectively, the said last parts being constructed and arranged to hold the said member resiliently in operative 95 position, and to release or engage it upon being slightly forced beyond fully extended position.

In testimony whereof I have affixed my signature.

RALPH C. WEBSTER.
